UNITED STATES PATENT OFFICE

102,026

DESIGN FOR A COMBINED ICE CREAM FREEZER AND DISPLAY COUNTER

Everett B. Eckland, Oak Park, Ill.

Application March 28, 1936, Serial No. 61,828

Term of patent 7 years

To all whom it may concern:

Be it known that I, Everett B. Eckland, a citizen of the United States and a resident of Oak Park, in the county of Cook and State of Illinois, have invented a new, original, and ornamental Design for a Combined Ice Cream Freezer and Display Counter, of which the following is a specification, reference being had to the accompanying drawing, forming a part thereof.

In the drawing:

The figure is a perspective view of a combined ice cream freezer and display counter showing my design.

I claim:

The ornamental design for a combined ice cream freezer and display counter as shown.

EVERETT B. ECKLAND.
